UNITED STATES PATENT OFFICE.

GEORGE H. HIGGINS, OF CORTLAND, NEW YORK, ASSIGNOR TO THE BREWER-TITCHENER CORPORATION, OF CORTLAND, NEW YORK, A CORPORATION OF NEW YORK.

METHOD OF FORGING INSULATOR CAPS.

Application filed October 27, 1927. Serial No. 229,177.

This invention relates to the art of hollow metal forgings and more particularly to a one-piece cap or socket adapted to securely mount therein an insulator disc of the suspension type as used in connection with high-tension electric transmission lines or the like. The primary object of my improved method is to effectively and economically make a chambered product of this character by a combined solid forging and expanding process as distinguished from the same article made by means of a casting process or complete forging process.

Insulator caps of the suspension type are generally formed in the shape of an open-mouthed bell of which its dome is equipped with an integral attachment means that serves for supporting purposes while the interior of such a hollow cap is usually provided with an undercut mouth lip or rim means adapted to secure a cement medium and positively hold the neck of an insulator disc within the cap socket.

A protective cap of this kind is ordinarily interposed between each of a series of spaced multiple insulator units mounted in tandem and the number of units so strung together being dependent upon the transmitted high tension line voltage; it will be obvious that the metal spacing caps in question must possess the utmost of reliability as to structural material for the reason that it has proven extremely difficult as well as expensive to replace any defective cap once it has been placed in service.

The present invention seeks to promote the quality and uniformity of such products by means of an improved forging process. The use of worked metal insulator caps particularly when forged of high grade carbon or alloy steel, allows of making their wall thickness relatively thin owing to the finer and closer grain that results from swaging the metal; it also affords a more uniform and stronger molecular material structure than is attainable by casting methods. In addition, my forging method reduces the material and shipping weight required for safely carrying a specified suspended line load and generally makes for a more compact insulator assembly as compared with the cast type of cap.

My present invention in certain particu-

lars represents an improvement in method and construction over the disclosure made in the Clinton W. Stover Patent No. 1,463,601 as granted July 31, 1923. To this end and the accomplishment of other new and useful results, my invention further consists in novel features of structure and manipulation, all of which will hereinafter be more fully described.

Reference is had to the accompanying two sheets of drawings which are illustrative of a specific embodiment of my invention particularly as applied to forged insulator caps of the socket type, in which drawings like characters of reference indicate like parts, and in which:

Fig. 1 represents an assembly of a series of alternate insulator discs arranged in tandem, each interconnected by means of my interposed cap devices and intended as a whole to suspend a high tension transmission line.

Fig. 2 shows an enlarged transverse sectional view as taken through one of the tandem insulator units indicated in Fig. 1.

Fig. 3 illustrates in perspective, one shape of stock from which my cap may be forged.

Fig. 4 shows in plan a blank comprising a flanged disc provided with a centrally extruded support lug that may initially be shaped up out of said stock, while Fig. 5 shows a section thereof as taken along line 5-5 of Fig. 4.

Fig. 6 indicates the manner in which the circumscribing flange portion of said blank may next be drawn up into a cup-shape whose skirt is provided with a relatively small mouth dimension.

Fig. 7 shows how this mouth may be undercut by expanding outwardly the skirt portion that lies contiguous to the cup rim, while Figs. 8 and 9 show the respective circular end view contours thereof.

Fig. 10 illustrates a rolling method by which the undercutting of the cup mouth may readily be accomplished by an expanding operation.

Fig. 11 shows the manner in which my integral supporting lug may be recessed to fashion same into a socket type of insulator cap, and Fig. 12 shows a top view of said socket recess thus formed.

Figs. 13 to 15 inclusive represent various

views of an alternative method of shaping up my solid supporting lug which is here cut into two spaced ear lugs or straps for hanger attachment purposes.

Referring first to Fig. 1, this shows a series of multiple insulator discs such as A', A'', etc. of which the uppermost one may be suspended in any suitable manner from a cross arm C4 or the like as carried by a pole or transmission line tower; these discs may be respectively interconnected in tandem by means of the interposed chambered metal caps B', B'', etc. which cooperate with complementary link members C2 to form a built-up composite insulator in the conventional fashion and of which the lowermost disc is usually provided with a conductor clamp C1 that carries the high tension transmission wire C3.

Fig. 2 shows in enlarged scale, the principal structural features of one such insulator unit and it will be observed that any intermediate metal cap such as B'' is provided with a flared tubular skirt portion E3 and that each such cap may be further equipped with an integrally formed supporting lug means such as E2 which in the present instance, is shown as of the socket type. The mouth or lip edge of said bell-shaped cap is equipped with an undercut rim member E4' adapted to snugly receive and mount the neck A1'' of the glass, porcelain or similar style of petticoat insulator disc A''. This disc may further be provided with a centrally disposed disc socket A2'' into which the free shank end of the headed link pin C2 may be firmly cemented or otherwise secured, while the insulator neck A1'' may likewise be fastened into the radially undercut cap cavity or socket, preferably by means of cement or other suitable filler medium indicated as A3''. In close adjacency to the restricted rim E4' there is provided an internally disposed groove E3' that extends radially beyond the final dimension given to the rim mouth of my cap so as to afford an undercut chamber into which said cement medium may be poured and allowed to set; whereupon because of its enlarged shear area, said cement is made capable of safely resisting neck displacement against a heavy line load. The dome of my cap is preferably secured to the lower end of its suspending link through a pivot type of joint about which the cap may oscillate.

Taking up now the making of a cap structure by my improved forging process, the first step may reside in rough forging down the bar or plate stock D illustrated in Fig. 3 or the like, into a relatively thin blank E represented by Figs. 4 and 5. Said blank shows a pancake like or disc portion E1 whose central portion is extruded into a somewhat rounded projecting lug member

E2 and which particular gathering of the metal is subsequently utilized to form an integral support means for my finished insulator cap. If desired, said flat disc portion E1 may initially be given a flared or an upwardly dished profile marked E1' and it will be understood that either of such blank shapes are intended to be forged up by means of suitable dies.

The surrounding disc portion E1 of my blank may now be bent or drawn up into the cap shape shown in Fig. 6 and this step may either be performed by means of a single or successive stage cold drawing process through the use of a suitable press equipment with the necessary dies, it is preferred however to perform this step by a hot forging process in a single heat with the initial formation of said blank; should the latter method be resorted to, the forging of said bar or plate stock D by the gang method into the successive forms shown in Figs. 4 to 6 inclusive, virtually constitutes a single or primary shaping operation or step. As will be apparent, the end in view is to fashion the forged metal into the cup shape that is represented in Fig. 6 in which the flared disc portion E1 has been brought up into the tubular cup-like skirt portion E3 that terminates in the rim E4 and which skirt preferably conforms to a substantially straight-line diverging profile having a relatively small mouth opening or initial inside rim dimension designated as "M". The opposite end of said skirt portion E3 is closed by the transverse dome or crown wall portions E5; near the center of the exterior surface of said dome wall, there is integrally attached the lug E2 as originally shaped up with said blank, it being pointed out that the integral formation of the support element of my swaged insulator cap constitutes an important feature of the present invention.

As a further step in the making of my insulator cap, said rim E4 is now undercut in a single expanding operation in the fashion cross-sectionally represented in Fig. 7. The circumferential skirt wall E3 portion lying contiguous to the cap mouth has thereby been swaged radially outward by means of the indented bulge E3' to constitute an undercut endless groove with respect to the original straight-line profile shape of said skirt wall that is indicated by dotted and dashed outline. This particular step may be performed by any suitable expanding method but it is preferred to use complementary inside and outside rolls, such for instance as F1 and F2 that are schematically represented in Fig. 10; the complementary peripheries of these rolls are properly shaped to expand said straight line skirt profile into the interiorly bulged profile E3' described in connection with Fig. 7. Said

inside roll F1 may be given a relatively small diameter as indicated and made laterally movable for the purpose of exerting a heavy follow-up thrust against the outer 5 roller F2 or backing member that rotates in the fixedly held bushing F3.

It is emphasized however that the essential element of my described skirt expanding means resides in said inner roller means F1 10 which forming or spinning implement when inserted into the mouth M of a cup shape, is adopted to apply radially directed pressure against the interior of said skirt and thus in a single operation, roll out the endless channel-like groove E3' disposed inwardly of the rim E4.

It will further be observed that the inner diameter "M" given to the rim mouth may be kept fixed once the disc E1 is bent up into 20 the shape shown in Fig. 6, and that this sized neck diameter need not thereafter be disturbed by the expanding operation such as would apply when operating in a reverse manner in accordance with the Stover patent 25 method where the mouth of his forged cap is finally cupped inwardly to form an undercut that subsequently fixes the inside diameter of his contracted neck mouth. After my cap has been internally grooved by the 30 cited expanding or bulging method, the rim E4 may if desired, be trimmed down to form a finished rim mouth E4' as indicated in Fig. 7, it being apparent that the cross-sectional 35 shape of cap here shown is representative of a plane figure that by its revolution about the axes X—X, preferably generates a symmetrically shaped cap cavity or socket chamber.

Finally, the lug E2 of my completely 40 forged and expanded cap may be machined to form up a socket chamber E6 such for instance as is shown in Figs. 11 and 12, and this may be milled or hot sawed out of the solid dome lug. This particular style of lug 45 socket is intended to cooperate for cap support purposes with a link pin C2 having a rounded or ball head enlargement C2' which is adapted to be removably received within said undercut socket E6 and to engage with the overhanging ledge portions E2' thereof, in the ball and socket manner represented in 50 Fig. 2. In order to secure said head against inadvertent displacement, the cotter pin E7 may be inserted through the drilled hole E8 55 of the hollowed lug.

As an alternative support means, said extruded lug E2 may if preferred, be given a slightly modified shape to allow of its being machine slotted into the complementary 60 spaced dome ears E9 and E9' as indicated in Figs. 13 to 15; these ears may thereupon be drilled to mount the through toggle pin E10 that engages with a somewhat different type of link pin C2 which in this instance, is

provided with a journaled stub-end enlargement C2" of the clevis type.

Both the described socket or ear types of cap supports are now in common use, and my invention in part consists in integrally forming either of such attaching means by improved one-piece swage methods and in which the lug E2 may be merged by the use of ample fillets such as E2" which afford a perfectly smooth exterior that can readily be uniformly and flawlessly galvanized throughout all of the exposed cap surfaces for rust preventive purposes. The filleted integral tie of my support lug obviates all inaccessible pockets or crevices such as would have to be contended with were said lug ears 80 or sockets separately fabricated and then attached by welding or rivet means, it being apparent that any such surface irregularities are difficult to galvanize evenly with an unbroken protective coating capable of withstanding prolonged weathering. In addition, my forged insulator cap allows of keeping the crown or dome wall E5 relatively thin which in turn holds the overall height dimension at a minimum; the smooth interior of my cap not only facilitates the secure and compact mounting of the insulator neck into the cap recess but the avoidance of any sharp projections near the cap mouth, augments the dielectric breakdown resistance 95 against high-tension voltage.

Furthermore, I am able to closely maintain said inside or mouth diameter "M" to any predetermined dimension and that owing to the superior quality of the swaged 100 cap metal, its ultimate holding power against a severe pull load is unexcelled; any waste by defective caps is also materially reduced over that prevailing in the manufacture of the cast type of caps and 105 the chances for hidden defects getting by on inspection are decidedly remote because well made articles of the forged type generally enjoy a striking reputation for reliability and uniformity of product. My described method therefore allows of producing a finished insulator cap that is of the highest grade and one that is in all respects admirably suited to the intended purposes.

It will be understood that various changes in the details and mode of manipulation may be resorted to in carrying out the described forging method of making insulator caps or the like, and that my process is intended to include the equivalent thereof in stamped metal products, also that while it may be desirable to hold to the cited mouth dimension "M" that is initially given my cup, it may at times prove expedient to enlarge or even reshape such original mouth formation during my final expansion step, all without departing from the spirit and

scope of my invention heretofore described and more particularly pointed out in the appended claims.

I claim—

6. 1. The method of making from bar or plate stock, a one-piece supportable insulator cap of the undercut socket type or the like, and which method consists in swaging up said stock into a cup-like shape comprising a tubular skirt portion having an open lip end with the other end thereof closed by a crown wall provided with an exteriorly extruded supporting lug means, and then introducing therein a groove forming implement which by virtue of a radially exerted swage pressure is adapted to expand the lip region of said skirt into an outwardly bulged groove that is radially undercut with respect to the final lip end opening of said skirt. 70
10. 2. The method of making from bar or plate stock, a one-piece supportable insulator cap of the undercut socket type or the like, and which method includes forming said stock into a cup-like shape comprising a tubular skirt portion of which the open rim end is brought to a predetermined mouth dimension while the other skirt end is closed by a dome wall portion from the exterior surface of which dome there is extruded a lug means adapted to support said cap, and then introducing into said mouth a forming implement which by the application of interiorly applied surface pressure is adapted in a single operation to bulge out the skirt region contiguous to said rim into a channel-like groove means that extends radially beyond the final mouth dimension. 75
15. 3. The method of making from bar or plate stock, a one-piece supportable insulator cap of the undercut socket type or the like, and which method includes forming said stock into a cup-like shape comprising a tapered tubular skirt portion having a substantially straight-line cross-sectional profile and of which skirt its larger end is kept open to constitute a mouth while the smaller skirt end is closed by a dome wall portion carrying an exteriorly extruded lug means for cap supporting purposes, and thereupon introducing into said mouth a forming implement including a roller means adapted to expand outwardly the rim region of said skirt into a undercut groove means that extends radially beyond the final mouth dimension of said skirt. 80
20. 4. The method of making from bar or plate stock, a one-piece supportable insulator cap of the undercut socket type or the like, and which method includes swaging said stock into a disc-like blank provided with an extruded cap supporting lug means that projects out of one disc face near the center thereof, then bending up the lug enclosing disc portion into a cup-like shape comprising a tubular skirt portion having a mouthed rim end while the other skirt end is closed by a dome wall portion with said extruded lug disposed to project from the exterior surface thereof, and lastly, introducing therein a forming implement adapted to expand outwardly the rim region of said skirt into a channel-like groove that is radially undercut with respect to the final rim mouth dimension. 85
25. 5. The method of making from bar or plate stock, a one-piece supportable insulator cap of the undercut socket type or the like adapted to be supported by link pin means, and which method includes forming said stock into a cup-like shape comprising a tubular skirt portion having a mouthed rim end while the other skirt end is closed by a dome wall portion from the exterior surface of which an extruded solid cap supporting lug means projects, then introducing a pressure exerting implement into the rim mouth which upon relative rotation between said implement and the skirt is adapted to roll outwardly the rim region of said skirt into an endless channel-like groove that is radially undercut with respect to the final rim mouth dimension, and lastly, trimming off a portion of the tubular skirt rim that extends beyond the outermost of said channel edges. 90
30. 6. The process of making from bar or plate stock, a one-piece supportable insulator cap of the undercut socket type and securely mounting therein an insulator disc neck, said process including forming said stock into a cup-like shape comprising a tubular skirt portion having a mouthed rim end while the other end is closed by a dome wall portion from the exterior surface of which dome there is extruded an integral lug means adapted to support said cap, and thereupon introducing a pressure exerting implement adapted to bulge out the skirt region contiguous to said rim and generate an endless undercut groove means that extends radially beyond the final expanded dimension given to said mouth. 95
35. 7. The method of making from bar or plate stock, a one-piece supportable insulator cap of the undercut socket type or the like provided with smooth exterior and interior surfaces, and which method includes hot forging said stock into a cup-like shape comprising a tubular skirt portion having a mouthed rim end while the other skirt end is closed by a rounded dome wall portion from the exterior surface of which dome there is extruded an integrally filleted lug means, then introducing a forming implement serving to exert radial pressure against the interior of the rim region of said skirt and which implement is adapted in a single operation to expand an undercut groove means that is radially undercut with 100
40. 8. The method of making from bar or plate stock, a one-piece supportable insulator cap of the undercut socket type or the like, and which method includes forming said stock into a cup-like shape comprising a tubular skirt portion having a mouthed rim end while the other end is closed by a dome wall portion from the exterior surface of which dome there is extruded an integral lug means adapted to support said cap, and thereupon introducing a pressure exerting implement adapted to bulge out the skirt region contiguous to said rim and generate an endless undercut groove means that extends radially beyond the final expanded dimension given to said mouth. 105
45. 9. The method of making from bar or plate stock, a one-piece supportable insulator cap of the undercut socket type or the like, and which method includes swaging said stock into a disc-like blank provided with an extruded cap supporting lug means that projects out of one disc face near the center thereof, then bending up the lug enclosing disc portion into a cup-like shape comprising a tubular skirt portion having a mouthed rim end while the other skirt end is closed by a dome wall portion with said extruded lug disposed to project from the exterior surface thereof, and lastly, introducing therein a forming implement adapted to expand outwardly the rim region of said skirt into a channel-like groove that is radially undercut with respect to the final rim mouth dimension. 110
50. 10. The method of making from bar or plate stock, a one-piece supportable insulator cap of the undercut socket type or the like, and which method includes forming said stock into a cup-like shape comprising a tubular skirt portion having a mouthed rim end while the other end is closed by a dome wall portion from the exterior surface of which dome there is extruded an integral lug means adapted to support said cap, and thereupon introducing a pressure exerting implement adapted to bulge out the skirt region contiguous to said rim and generate an endless undercut groove means that extends radially beyond the final expanded dimension given to said mouth. 115
55. 11. The method of making from bar or plate stock, a one-piece supportable insulator cap of the undercut socket type or the like provided with smooth exterior and interior surfaces, and which method includes hot forging said stock into a cup-like shape comprising a tubular skirt portion having a mouthed rim end while the other skirt end is closed by a rounded dome wall portion from the exterior surface of which dome there is extruded an integrally filleted lug means, then introducing a forming implement serving to exert radial pressure against the interior of the rim region of said skirt and which implement is adapted in a single operation to expand an undercut groove means that is radially undercut with 120
60. 12. The method of making from bar or plate stock, a one-piece supportable insulator cap of the undercut socket type or the like, and which method includes swaging said stock into a disc-like blank provided with an extruded cap supporting lug means that projects out of one disc face near the center thereof, then bending up the lug enclosing disc portion into a cup-like shape comprising a tubular skirt portion having a mouthed rim end while the other skirt end is closed by a dome wall portion with said extruded lug disposed to project from the exterior surface thereof, and lastly, introducing therein a forming implement adapted to expand outwardly the rim region of said skirt into a channel-like groove that is radially undercut with respect to the final rim mouth dimension. 125
65. 13. The method of making from bar or plate stock, a one-piece supportable insulator cap of the undercut socket type or the like, and which method includes forming said stock into a cup-like shape comprising a tubular skirt portion having a mouthed rim end while the other end is closed by a dome wall portion from the exterior surface of which dome there is extruded an integral lug means adapted to support said cap, and thereupon introducing a pressure exerting implement adapted to bulge out the skirt region contiguous to said rim and generate an endless undercut groove means that extends radially beyond the final expanded dimension given to said mouth. 130
70. 14. The method of making from bar or plate stock, a one-piece supportable insulator cap of the undercut socket type or the like, and which method includes swaging said stock into a disc-like blank provided with an extruded cap supporting lug means that projects out of one disc face near the center thereof, then bending up the lug enclosing disc portion into a cup-like shape comprising a tubular skirt portion having a mouthed rim end while the other skirt end is closed by a dome wall portion with said extruded lug disposed to project from the exterior surface thereof, and lastly, introducing therein a forming implement adapted to expand outwardly the rim region of said skirt into a channel-like groove that is radially undercut with respect to the final rim mouth dimension. 135

respect to the final mouth opening of said skirt.

8. The method of making an insulator cap from a blank bar which includes forging a cup and extruding an ear lug on its bottom, and then introducing a groove forming implement which by radial pressure ex-

erted upon the skirt interior is adapted in a single operation to expand the mouth of the cup into an undercut bead disposed inwardly **10** of the cup edge.

In testimony whereof, I have herewith set my hand this 26th day of October, 1927.

GEORGE H. HIGGINS.
